UNITED STATES PATENT OFFICE

109,669

DESIGN FOR A DRESS

Margaret Michelson, New York, N. Y.

Application February 10, 1938, Serial No. 75,026

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the particular waist and hip section which is folded at intervals as disclosed, in combination with a high necked waist section with corresponding patch shirrings at the shoulders and bosom, as shown.

I claim:

The ornamental design for a dress, substantially as shown and described.

MARGARET MICHELSON,
